UNITED STATES PATENT OFFICE

JAMES CUSHING, OF DUBUQUE, IOWA.

APPARATUS FOR MAKING VINEGAR.

SPECIFICATION forming part of Letters Patent No. 249,161, dated November 8, 1881.

Application filed December 21, 1880. (No model.)

To all whom it may concern:

Be it known that I, JAMES CUSHING, of Dubuque, in the county of Dubuque and State of Iowa, have invented a new and useful Improvement in Apparatus for Making Vinegar; and I do hereby declare that the following is a full and exact description of the same, reference being had to the accompanying drawings, and to the letters of reference marked thereon.

10 In the use of vinegar-generating apparatus it has been found that a long or tall generator possesses great advantages over a shorter one, principally for the reason that in its passage from top to bottom the liquid to be acetylated is longer exposed to the action of the air, and consequently stronger vinegar is made in less time; but a number of difficulties are encountered in using a tall generator. First, in all those generators now in use some portions of the 20 vessel are narrower than others, and in these narrow parts the porous mass, usually composed of shavings or corn-cobs, becomes tightly packed in and wedged together, so that the liquid cannot easily percolate through it, or perhaps will pass through it in large streams, and so would not be sufficiently exposed to the atmosphere; second, the "mother," which always accumulates in the generator, forms around the individual pieces of the porous 25 mass, and so renders it impervious to the liquid; third, in the generators now used it is impossible to distribute the liquid equally, so that all may be properly exposed to the air. This has been attempted by passing it through 30 sieves, but the mother will accumulate and stop up the holes, and besides the liquid will still fall in drops or streams, instead of in a fine spray, as is most desirable. Again, the attempt has been made to flood the entire mass 35 with a large quantity of the liquid, but in this case the percolation was too rapid, and the oxidation did not take place properly.

The object of my invention is to obviate all these difficulties; and to this end my invention 40 consists, first, in the construction of a tall generator, having straight sides and divided by one or more partitions having apertures through which the liquid passes; second, in the construction of a series of cups, tubes, and distributors, by means of which the liquid is distributed equally over the porous mass; third,

in the arrangement of tubes by which air is admitted to the liquid; and, finally, in the novel arrangement and combination of all these various parts, as will be more fully hereinafter 55 explained.

In the annexed drawings, Figure 1 is a sectional view of the generator; Fig. 2, a plan view of the same; Fig. 3, a view of one of the plugs, with its distributor; Fig. 4, of one of the cups; Fig. 5, a top view of one of the slats *e*; Fig. 6, a bottom view of one of the slats *e*; Fig. 7, a plan view of one of the partitions, showing the arrangement of slats *e* therein; and Fig. 8, a view of the fastening for the 60 hoops.

The generator shown is divided into only three sections by the partitions, but in practice a larger number is usually required. Sometimes the rooms in which these generators are placed are not very high, and the generator may not be more than ten feet long, and only one set of straight staves used, running the entire length, with a partition in the middle, and sometimes of only one partition and two sections. The generator may be made of any length to accommodate itself to the room in which it is set up; but I prefer to make them about thirty-two or thirty-three feet high and in five or six detachable sections.

A B C are the three sections of the generator, each having the same diameter, and being about six feet in height. The staves of which they are formed are straight and beveled at the edges, so as to form the curve of the cask. 70 The ends of the casks are cut in in the manner shown, so that each one is set into the next below and there held firmly, so that the whole forms one continuous vessel. From top to bottom of this tank runs the small wooden tube 75 D, pierced with holes throughout its entire length, by means of which air is admitted to the liquid. The sides of the tank also contain holes for the same purpose.

E E' are partitions placed across the tank at 80 the points where the sections are joined. These partitions are composed of slats *e* &c., Fig. 5, passing across the tank, their ends being held in longitudinal grooves cut in the inside. These slats are boards about six inches in 85 width and varying in length, that of the longest being equal to the diameter of the cask,

and the others decreasing as they approach the sides. These boards have square notches cut in their sides, about two inches apart, which notches also extend entirely across the bottom 5 of the board, while the top remains smooth. The upper section, A, is filled up to about half its height with a mass of shavings, corn-cobs, &c. The middle sections, as B, are entirely filled with these substances. The lowest section, C, is divided by a secondary partition, b, and has its upper half filled with the porous mass, while the lower part is formed into a receiver, H, in which the vinegar accumulates until drawn off by the faucet e. The whole is 15 supported on suitable standards.

The head of the tank is pierced with a number of small holes. The proper number for one of the size shown is eighteen.

In the head of the generator, at different 20 points, are set six cups, d d, &c., as shown in Figs. 2 and 4. These cups are about three inches wide at the bottom, and decrease to about two inches at the top. They are made simply of a block of wood hollowed out on top 25 and having a projection on the bottom, by means of which they may be fastened to the head of the tank. In the upper rim of the cup are cut three notches, f f f, which are continued down the side of the cup until each connects 30 with a groove, h, cut in the head of the tank, and extending from the notch f to one of the eighteen holes above mentioned. In each of these holes is inserted a plug, i, of the shape shown in Fig. 3, having a hole, k, passing 35 through it longitudinally, and a larger hole, l, at right angles to the hole k, and passing from it to the outside of the plug. The plug is inserted in one of the eighteen holes, and is driven in until the hole l is level with the head 40 of the tank and opposite the end of one of the grooves h.

m m are cords fastened to the bottom of the plug and supporting the distributer n, which is a solid block of wood, preferably of cylindrical form and slightly concave on top. This 45 distributer may be made of any hard substance suitable for the purpose, such as earthenware; but I prefer to make it of wood, as it is cheaper, more readily made, and always easily obtained. 50 When I desire to feed faster I lengthen the cords m m, alluded to above; then if the liquid runs into and off from the end of plug i in a stream it will break up into drops before it strikes the distributer, provided it falls a sufficient distance. The best spray is found when 55 the liquid strikes the distributer in drops.

For holding together the staves of which the tank is composed, it is necessary to use heavy wooden hoops about three inches wide 60 by two inches thick. For securing the ends of these hoops I employ the fastening shown in Fig. 6. The ends of the hoop enter the iron clasps o o, to which they are bolted at p p. Each of these clasps has two ears or projections, r r, through which pass the screw-threaded bolts s s, provided with nuts by

means of which the clasps may be brought together and the hoops tightened.

The operation of my invention is as follows: The porous mass being placed in the tank in 70 the manner described, the liquid to be acetyfied is poured into the six cups d until it overflows through the notches f and runs down the side of the cup into the grooves h, thence along the grooves until it enters the hole l in the plug i 75 and passes through l and the lower half of the hole k. The object of having the hole k extend through the entire length of the plug is that when the mother accumulates in the lower part it may be easily removed. The liquid 80 drops from the pointed end of the plug i to the top of the distributer n, and the drops, striking its surface with considerable force, are broken up and converted into a fine spray or mist, which falls on the porous mass below. There 85 being so large a number of the distributors, they are but a short distance apart, and consequently the liquid is distributed in infinitesimal particles equally over the surface of the porous mass, and soaks through it gradually 90 instead of running in streams, while all the particles are equally exposed to oxidation. The liquid thus reaches the partition E and passes between the slats into the next section. The grooves and notches in the slats prevent 95 the liquid from running along the edges and accumulating in large drops, and cause it to fall from the numerous projections to the mass below in the same small particles as before. The liquid thus continues in its descent, passing 100 through one partition after another, until it finally reaches the receiver H and is drawn off through the faucet e.

Should the passage of the air through the tube D result in lowering the temperature too 105 much, a plug is inserted in the lower end, and the current stopped until the interior again becomes sufficiently warm.

If the mother should accumulate in either of the sections to too great an extent, it may 110 be easily detached and cleansed.

The partitions act also as supporters for the mass above.

What I claim as my invention, is—

1. A vinegar-generator composed of one section or several detachable sections of the same diameter, and having straight sides, and divided, substantially as described, by one or more partitions composed of slats grooved at the edges and on the bottom, as and for the 115 purposes set forth.

2. In a vinegar-generator, a series of one or more partitions composed of slats grooved at the edges and on the bottom, substantially as and for the purpose described.

3. In a vinegar-generator, the cups d d, having the notches f f, substantially as and for the purpose described.

4. In a vinegar-generator, the combination of the cups d d, having the notches f f, with 120 the grooves h h, substantially as and for the purpose described.

5. In a vinegar-generator, and in combination, a series of plugs, *i*, and distributors *n*, constructed and arranged substantially as described and shown.
- 5 6. The combination of the plug *i*, cords *m m*, and distributor *n*, substantially as and for the purpose set forth.
7. In a vinegar-generator, a series of cups, *d*, grooves *h*, plugs *i*, and distributors *n*, substantially as and for the purpose described.
- 10 8. In a vinegar-generator, the combination, with a tank having straight sides, of a series of one or more partitions composed of grooved and notched slats, substantially as and for the purpose described.
- 15 9. A vinegar-generator, substantially as de-

scribed, provided with a central tube, *D*, extending from the top through the bottom thereof, and adapted to distribute the exterior air therein, substantially as set forth. ²⁰

10. In a vinegar-making apparatus, the combination of the cups *d*, grooves *h*, plugs *i*, and distributors *n*, with the straight-sided sections *A B C*, partitions *E E'*, and receiver *H*, substantially as and for the purpose set forth. ²⁵

This specification signed and witnessed this 18th day of November, 1880.
